(57) **CLAIM**

The ornamental design for an autoclave, as shown and described.

DESCRIPTION

FIG. 1 is a plan view of an autoclave;

FIG. 2 is a front view thereof;

FIG. 3 is a bottom view thereof;

FIG. 4 is a left side view thereof;

FIG. 5 is a right side view thereof;

FIG. 6 is a rear view thereof; and,

FIG. 7 is a perspective view from upper right side thereof; and,

FIG. 8 is an enlarged view of the control panel thereof.

The broken lines are included for the purpose of illustrating portions of the autoclave that form no part of the claimed design.
